UNITED STATES PATENT OFFICE

GEORGE C. HABICHT, OF SNYDER, NEW YORK

RAIL TIE PLATE AND FASTENER

Application filed March 13, 1930. Serial No. 435,433.

This invention relates generally to improvements in the tie plates employed for anchoring railroad rails to the ties, but more particularly to a plate designed for use with 5 concrete or similarly constructed ties.

One of its objects is to provide a tie plate of this character which is simple, compact and inexpensive in construction, and which employs reliable and effective means for securely holding the rails against creepage relative to the ties.

Another object of the invention is the provision of a tie plate for concrete ties having effective and efficient means for not only anchoring the rail against longitudinal and transverse displacement but for reliably holding it against vertical displacement and eliminating play between the tie plate and the rail.

Still further object is to provide a tie plate of this character which dispenses with spikes, bolts or equivalent auxiliary fastening devices and in which its parts are so designed and constructed as to effect their ready 25 assemblage within a minimum period of time and to afford greater safety of travel.

In the accompanying drawings:—

Figure 1 is a perspective view of a railroad rail and tie showing my improved tie plate in connection therewith. Figure 2 is an enlarged cross section taken in the plane of line 2—2, Figure 1. Figure 3 is a vertical section taken on line 3—3, Figure 2. Figure 4 is a sectional perspective view of the tie plate. Figure 5 is a perspective of one of the locking keys.

Referring now to the drawings, 10 indicates one of the ties, which, for the purpose of my invention, are made of concrete or like 40 material, and 11 indicates one of the railroad rails.

My improved fastening means for securing the rail to the ties consists of a tie plate 12 made of malleable iron or other appropriate material and of substantially rectangular shape in plan. Depending from the opposite ends of this plate are anchoring elements 45 or yokes 13 adapted to be embedded in the concrete tie for securely holding the plate thereon. As shown in Figure 1 of the draw-

ings, these anchoring yokes are preferably U-shaped to effectually hold the plate against longitudinal and transverse displacement as well as vertical displacement relative to the tie. While the anchoring elements are 55 shown as being practically integrally united with the tie plate, whereby the tie plate is anchored to the tie during its manufacture, it is to be understood that, if desired, the yokes 13 may be independently embedded in 60 the tie and the plate provided with openings adjacent its four corners for receiving the yoke-shanks and bolting said plate thereto.

Formed integrally with the tie plate and rising from the opposite sides of its rail-bearing surface are opposing hook-shaped lugs or projections 14 whose inner, angularly-disposed faces 15, 16 are spaced a suitable distance from the longitudinal edges of the rail base and from the top sides thereof, 70 respectively, as seen in Figure 2. The inner edges of the overhanging lug-flanges 17 preferably terminate at a point to provide a gap between them of sufficient width to allow for the free passage of the rail-bar between them in effecting the application and removal of the rail to and from the tie plate. Adapted for insertion in the resulting spaces formed between the lugs 14 and the adjoining portions of the rail 11 are keys or L-shaped locking bars 18 which serve to reliably clamp the rail to the tie plate. The upright portion 19 of each key rests at its lower edge on the tie plate and its opposite side faces engage the lug-face 15 and the adjoining edge of the rail-base, respectively. The horizontal portion 20 of the key overhangs the rail-base with its underside engaging the marginal top side of the latter and with its top side engaging the lug-face 80 85 90

16. In order to effect a firm gripping action of the keys 18, their upper and lower faces 21, 22 are slightly inclined in the direction of their length and in substantially parallel relation, and the corresponding contiguous faces of the lug-flanges 17 and tie plate 12 are similarly inclined, the bearing face of the plate being preferably formed by a recess or notch 23 having an inclined bottom disposed substantially parallel to and vertically be- 100

neath the face of said lug-flange. The undersurface of the key portion 20, as regards the direction of its length, is parallel with that of the rail-base while crosswise of the latter it conforms to the inclination of the top surface thereof. By this construction, a practically double, wedge-like action is produced between the locking keys and the contiguous bearing walls of the tie plate and rail, thereby effectually holding the rail onto the plate to prevent its vertical displacement and positively resisting creepage of the rail relative to the plate. If desired, the top and bottom faces of the key-portions 20 may be provided with teats or button-like projections 24 which serve to increase the frictional grip between the parts and allow for any variation or unevenness in the surface contours of the parts with which the keys contact. When driving the keys into place, these teats may flatten out or be forced into the adjoining contacting surfaces and thereby afford a snug and tight fit to reliably retain the parts in place.

As shown in Figure 4, the bottoms of the companion recesses 23 in the tie plate are oppositely inclined crosswise of the latter, one key being driven into place from one side of the plate and the other from the opposite side thereof, whereby an effective gripping of the rail from opposite directions is obtained, the locking action of one key complementing that of the other. Further, by this arrangement, the same locking key is used for either side of the plate, thus eliminating the necessity of right and left for this purpose.

While my invention is particularly intended for use in connection with railroad rails, it may be used with equal effect in structural steel work.

I claim my invention:—

1. A fastening device for railroad rails and the like, comprising a plate adapted for attachment to a support, hook-shaped lugs rising from opposite sides of said plate for receiving the rail between them in spaced relation thereto, the underside of the overhanging portion of each lug being inclined in a direction lengthwise of the rail and the top side of the plate beneath said overhanging hook-portion being similarly inclined, and locking bars disposed in the spaces between the rail and said plate-lugs and each having its top and bottom faces inclined in substantially parallel relation to the opposing inclined sides of the plate and its hook.

2. A fastening device for railroad rails and the like, comprising a plate adapted for attachment to a support, hook-shaped lugs rising from opposite sides of said plate for receiving the rail between them in spaced relation thereto, that part of the plate beneath each overhanging hook-portion having a recess therein substantially parallel to

the rail, and substantially L-shaped locking bars disposed in the spaces between the rail and said lugs, said bars engaging, in wedge-like fashion, the contiguous opposing faces of the rail and the lugs and seated at their lower edges in the corresponding plate recesses.

3. A fastening device for railroad rails and the like, comprising a plate adapted for attachment to a support, hook-shaped lugs rising from opposite sides of said plate for receiving the rail between them in spaced relation thereto, the underside of the overhanging portion of each lug being inclined in a direction lengthwise of the rail and the top side of the plate beneath its corresponding lug having a recess therein substantially parallel to the rail, the bottom of said recess being likewise inclined, and substantially L-shaped locking bars disposed in the spaces between the rail and said lugs and each embracing the contiguous longitudinal edge of the rail at its inner side and being embraced by the contiguous faces of the plate and lugs at its outer side, the upper and lower faces of each bar being inclined in accordance with the corresponding faces of the plate-lug and plate-recess and the underside of the overhanging portion of each bar conforming to the surface of the rail-base.
